S. SANTILLI

MOPPING MACHINE

Filed March 7, 1924

UNITED STATES PATENT OFFICE.

STEFANO SANTILLI, OF CANTON, OHIO.

MOPPING MACHINE.

Application filed March 7, 1924. Serial No. 697,521.

This invention relates to improvements in mopping machines designed for scrubbing floors or similar surfaces, and is of that general type including a reservoir for containing the cleaning water and means for discharging the water therefrom upon the surface to be cleaned, and a rotary mopping device for scrubbing the dampened floor.

The objects of the improvement are to 10 provide a scrubbing machine of this general type provided with a water reservoir having means for controlling the discharge of water therefrom, a rotary mopping device, a rotary squeegee for pressing the dirty water 15 from the mops and a tank for receiving the dirty water as it is squeezed from the mops.

An important object of the improvement is the construction of the rotary squeegee, wherein a plurality of wedging surfaces are 20 provided for successfully acting upon the mops for squeezing the water therefrom, a series of pockets being formed in the rotary squeegee communicating with the wedging surfaces to receive the dirty water squeezed 25 from the mops and transfer the same to the tank provided for that purpose.

The above and other objects may be attained by constructing the machine in the manner illustrated in the accompanying 30 drawing, in which—

Figure 1 is a longitudinal sectional view through the improved mopping machine;

Fig. 2, a section on the line 2—2, Fig. 1; and

Fig. 3, a fragmentary sectional view showing the gearing designed for operating the mopping mechanism by traction.

Similar numerals refer to similar parts throughout the drawing.

The housing 1 of the machine may be of 40 metal or wood, and is provided in its lower portion with the rearwardly disposed projection 2. The front and rear walls of the housing may be inclined toward each other at their upper ends as at 3 and 4 respectively, 45 terminating in the reduced upper portion 5, provided with a removable cover 6.

The cleaning water receptacle 7 is located in the upper reduced portion of the 50 housing, a ledge 8 upon the rear wall supporting the rear portion of said receptacle. A reduced portion 9 communicates with the forward side of the reservoir, extending downward and forward along the inclined 55 portion 3 and then downward at an angle communicating with the enlarged cylindri-

cal portion 10 located in the lower forward part of the casing.

The cylinder 10 is provided with perforations 11 in its lower side to permit the cleaning water to be discharged upon the floor or other surface over which the machine is passed.

For the purpose of controlling the flow of water, a valve is provided which may be in 65 the form of a split cylindric slide valve 12, mounted for rotation around the axis of the cylinder 10 and provided with a handle 13 extending through a slot 14 in the front portion of the casing. As shown in Fig. 1, this 70 valve may be operated to entirely close the apertures 11 if desired.

The housing 1 is mounted upon rollers 15 in order that the machine may be moved over the floor as by a handle 16. A bail 17 may 75 be connected to the upper portion of the housing for lifting the mopping machine when it is desired to transport the same from place to place.

The rotor 18 is mounted upon a shaft 19 80 journaled through the side walls of the housing. This rotor is provided with a plurality of arms 20 having the clamping plates 21 carried at their end portions by means of the clamping screws 22. A mop 23 is 85 clamped beneath each of the clamping plates and arranged to extend over the end of the arm as shown.

The rotary squeegee is shown at 24 and is 90 fixed upon a shaft 25 journaled through the side walls of the housing and parallel to the rotary shaft 19. This rotor is provided with a plurality of wedge shaped radial ribs 26, the outer edge of each of which is curved as shown at 27, pockets 28 being provided 95 between the ribs. An end plate 29 is provided at each end of the rotor in order to retain water in the uppermost pockets, as shown in Fig. 1.

A tank 30 is mounted upon the shelf 31 100 located in the lower portion of the reduced extremity 2 of the housing, to receive the dirty water which is squeezed out of the mops by the rotary squeegee. This tank is slidably mounted upon the shelf 31 and provided with a handle 32 by means of which it may be removed when it is necessary to empty the water therefrom.

The rotor and squeegee may be operated by a motor 33 as shown in Fig. 2. A sprocket 34 may be fixed upon the shaft 35 of the motor and connected by a sprocket chain 110

36 with a sprocket 27 upon the shaft 19 of the rotor.

Movement may be imparted to the rotary squeegee from the rotor by a sprocket gearing comprising the sprockets 38 and 39 upon the shafts 19 and 25 respectively, connected by the sprocket chain 40. The rotor and squeegee will thus be rotated in the directions of the arrows shown in Fig. 1.

10 In the operation of the machine, the handle 13 of the valve 12 is moved in a direction to expose the apertures 11 in the under side of the cylinder 10, permitting a spray of water to be played upon the floor within 15 the forward portion of the housing.

As the machine is moved across the floor by means of the handle 16, the rotor will be turned in the direction of the arrow shown in Fig. 1, the mops 23 thereon successively 20 wiping the dampened floor, cleaning the same and taking up the water therefrom, and as each mop engages the rotary squeegee, the same will be wedged between the arcuate surface 41 of the rotor and the wedge 25 surfaces 27 upon the squeegee, squeezing the dirty water from the mop into the pockets 28 of the squeegee, the water being discharged from these pockets into the tank 30 as illustrated.

30 In Fig. 3 is shown a method of operating

the rotor and rotary squeegee by traction of the machine upon the floor. The traction wheel 42 is journaled upon a stub shaft 43 fixed in one side wall of the housing and arranged to frictionally engage the floor or 35 other surface to be cleaned. A gear 44 is fixed to the traction wheel 42 and meshes with the pinions 45 and 46 mounted upon the rotary shaft 19 and squeegee shaft 25 respectively.

It will thus be seen that as the machine is moved across the floor, the wheel 42, frictionally engaging the floor, will be rotated and through the gear 44 and pinions 45 and 46, the rotor and squeegee will be rotated in 45 the same direction as shown in Fig. 1.

I claim:—

A mopping machine including a rotor, mops carried by the rotor and arranged to contact with the floor, a rotary squeegee provided with pockets and arranged to engage the mops to squeeze water therefrom, a receptacle located beneath the squeegee, and means for rotating the squeegee and rotor in the same direction regardless of the direction of movement of the mopping machine.

In testimony that I claim the above, I have hereunto subscribed my name.

STEFANO SANTILLI
